UNITED STATES PATENT OFFICE.

STANLEY STEMPKOSKI, OF LUKE, MARYLAND.

CHICKEN-COOP LOCK.

Application filed July 31, 1923. Serial No. 654,940.

To all whom it may concern:

Be it known that I, STANLEY STEMPKOSKI, a citizen of Poland, residing at Luke, in the county of Allegany and State of Maryland, ⁵ have invented certain new and useful Improvements in Chicken-Coop Locks, of which the following is a specification.

This invention relates to chicken coop locks and has particular reference to means ¹⁰ for preventing persons from gaining access to the interior of a coop during certain periods of the day.

An important object of the invention is to provide means for locking the door of a ¹⁵ chicken coop in such a manner that the said door cannot be unlocked while the chickens in the coop are occupying the roost.

A further object of the invention is to ²⁰ provide means for locking a chicken coop door, the said means being positioned entirely within the coop and under the control of the chickens while roosting so that access thereto cannot be obtained.

²⁵ Other objects and advantages of the invention will be apparent during the course of the following description.

In the accompanying drawings forming a part of this specification and in which like ³⁰ numerals are employed to designate like parts throughout the same.

Figure 1 is a diagrammatical view of a fragmentary portion of a chicken coop with the locking means employed for securing the ³⁵ door in its operative or locked position.

Figure 2 is a similar view to Fig. 1 and shows the means employed for operating the locking mechanism for unlocking the door.

Figure 3 is a similar view to Fig. 2 and ⁴⁰ shows in full and dotted lines the different positions occupied by the bolt keepers and operating means and further shows the means employed for actuating one of the bolt keepers for actuating the locking mechanism to lock the door.

Figure 4 is a fragmentary diagrammatical view of the locking mechanism viewed from above,

Figure 5 is a horizontal sectional view ⁵⁰ taken upon line V—V of Fig. 3.

Figure 6 is a perspective view of the locking bolt employed, and

Figure 7 is a perspective view of one of the keepers employed.

⁵⁵ In the drawings, wherein for the purpose

of illustration is shown the preferred embodiment of this invention, the numeral 5 designates the chicken coop in its entirety while the numeral 6 designates the door that is hingedly associated with the said coop ⁶⁰ and is adapted for closing the only entrance to the latter through which a person could pass.

Suitably secured to the side wall of the coop 5 in proximity to the door 6 is a framework 7 that is adapted for slidably supporting the bolt 8, which moves in a horizontal plane, and the pair of keepers 9 and 10 which move in vertical parallel planes. The bolt ⁷⁰ 8 is provided with a reduced extension 11 that is adapted for engaging one vertical edge of the door 6 for preventing the same from being opened. The opposite end of the bolt 8 is provided with a reduced extension 12 having connected thereto an L-shaped operating rod 13 which is provided with an eye portion 14 at its free end. The bolt 8 is further provided with a spring element 15 which is connected to a portion of the ⁷⁵ frame 7 and is adapted for normally retaining the bolt 8 in its locked position. The reduced extensions 11 and 12 carried by the bolt 8 provide vertically extending shoulders 16 and 17 respectively which are adapted to be engaged by the keepers 10 and 9 respectively for holding the bolt in its unlocked and locked positions. The keeper 9 is normally retained in a position for engaging the shoulder 17 for holding the bolt 8 in its locked position by means of the spring ⁸⁰ 18 and is connected at its upper end to a flexible cable or chain 19 which passes around the sheave 20 and is connected to one end of an operating lever 21 which is pivotally connected to the side wall of the ⁸⁵ coop 5 which carries the mechanism previously described. There is further provided a stop block 22 which acts as a support or rest for the operating lever 21. The side wall of the coop 5 is provided with a key ⁹⁰ hole 23 suitably positioned for allowing the insertion of the key 24, shown in Fig. 2, which moves the lever 21 into a vertical position for shifting the position of the keeper 9 to allow for the sliding of the bolt ⁹⁵ 8 to unlock the door 6. The keeper 10 is connected at its upper end to a flexible cable or chain 25 which passes upwardly over the sheave 26 and is connected at its outer end to the operating lever 27 which is provided ¹⁰⁰

¹¹⁰ to the operating lever 27 which is provided

with a stop or rest 28 that is employed for supporting the lever 27 in the manner shown. The wall of the coop 5 is provided with a key hole 29 through which the key 30, shown in Fig. 3, may be inserted for moving the lever 27 into a vertical position for shifting the keeper 10 upwardly to allow the bolt 8 to move into its locking position. In Fig. 2 there is shown a key 31 which may be inserted through the key hole 32 formed in one of the walls of the coop 5 for engaging the eye portion 14 of the pull rod 13 which is adapted for being employed to shift the bolt 8 into its unlocked position.

15 A roost support 33 is hingedly connected, as at 34 to a portion of the locked mechanism frame 7 and is resiliently connected by the spring 35 at its opposite end to the bracket 36, as shown. The free or resiliently supported end of this roost frame 33 is provided with a cross head 37 that is adapted for engaging the bracket 36 to limit the upward movement of the frame 33 and is further employed for engaging the stop 38 which prevents the support 33 from moving downwardly too great a distance. In Fig. 4 there is illustrated opposite side walls of the coop 5 which are provided with the roost supports 33 which carry the roost 39.

20 It is to be understood that the elements 33 to 37 inclusive are duplicated on the opposite side wall of the coop 5 to the wall which carries the locking mechanism previously described.

25 The operation of the locking mechanism is as follows:—

In Fig. 1 the door 6 is shown in its closed position and the bolt 8 is properly positioned for preventing the said door from being opened. When chickens are perched upon the roost 39, the support 33 with the cross head or guard 37 is weighted down against the pull of the spring 35 for causing the same to occupy the position shown in dotted lines. The cross head or guard 37 will obstruct the key hole 32 for preventing a person from inserting the key 31 to engage the pull rod 13 for shifting the bolt into its unlocked position. When the chickens have left the roost 39, such as in the morning after they have been locked up all night, the perch with its support 33 will be moved upwardly by the springs 35 for shifting the cross head or guard 37 out of alignment with the key hole 32. The key 31 may then be inserted through the opening 32 and positioned to engage the pull rod 13. The key 24 may then be inserted through the key hole 23 for engaging the operating lever 21. The key 24 is then pulled outwardly of the coop for moving the keeper 9 upwardly out of engagement with the shoulder 17 carried by the bolt 8. The bolt may then be moved to the position shown in Fig. 2 with the reduced extension

11 moved away from the door 6. The keeper 10, due to the downward pull of its spring 18, will be moved to engage the shoulder 16 carried by the bolt 8 for retaining the latter in its unlocked position. The keys 24 and 31 may then be disengaged from their respective operated elements and removed from the key holes 23 and 32 respectively. The door 6 may then be opened.

70 After the chickens have gone to roost at night, the door 6 may be closed and the key 30 may be inserted through the key hole 29 for engaging the lever 27 to move the keeper 10 upwardly against the tension of the spring 18. The spring element 15 connected to the bolt 8 will then move the latter into its position for locking the door 6. The movement of the bolt 8 will naturally cause the shoulder 17 to move laterally of the keeper 9 for allowing the spring 18 connected thereto to move it downwardly into engagement with the said shoulder. The bolt 8 is then securely held in its locked position by the keeper 9 and spring element 15. The previously described operation of 90 the mechanism may then be repeated the following morning for gaining access to the interior of the coop 5.

95 It is to be understood that the form of this invention herewith shown and described is to be taken as the preferred example of the same, and that various changes in the shape, size, and arrangement of parts may be resorted to without departing from the spirit of the invention or the scope of 100 the subjoined claims.

Having thus described the invention, I claim:—

1. In a device of the class described, the combination with a coop having a door, of 105 a bolt positioned within the coop, means for moving said bolt for holding said door in a closed position, said coop having an opening, means adapted to be inserted through said opening for moving said bolt 110 for releasing said door, and means controlled by the chickens for preventing the insertion of said last mentioned means.

2. In a device of the class described, the combination with a coop having a door, of 115 a bolt, holding means for retaining said bolt in its locking or unlocking positions, manually operated means for moving said bolt into its unlocking position, and means controlled by the chickens within the coop 120 for preventing the operation of the last mentioned means.

3. In a device of the class described, the combination with a coop having a door, of 125 a bolt positioned within said coop, means for moving said bolt into its locking or unlocking position, means for holding said bolt in said positions, said coop having an opening, means adapted to be inserted through said opening for moving said bolt 130

from its locking to its unlocking position, and means controlled by the chickens within said coop for preventing the insertion of said bolt operating means.

- 5 4. In a device of the class described, the combination with a coop having a door, of a bolt positioned within said coop, means for moving said bolt into its locking position, means for holding said bolt in its locking position, means for moving said bolt into its unlocking position, means for holding said bolt in its unlocking position, said coop having a plurality of key holes, a plurality of keys adapted to be inserted 70 through said key holes for operating the respective means referred to above for holding said bolt in its locking position, for moving said bolt into its unlocking position, and for holding said bolt in its unlocking 75 position, and means controlled from within said coop for preventing movement of said bolt into its unlocking position.
5. In a device of the class described, the combination with a coop having a door, of a bolt positioned within said coop, keepers for retaining said bolt in its locking or unlocking position, a resilient means for moving said bolt into its locking position, manually operable means controlled from the 80 exterior of said coop for moving said bolt into its unlocking position, means for operating said keepers, and means positioned within said coop and controlled by the chickens for preventing the movement of said bolt to its unlocking position.

6. In a device of the class described, the combination with a coop having a door, of a bolt positioned within said coop, means for moving said bolt into its locking position, manually operable means for moving said bolt into its unlocking position, and a resiliently supported roost within said coop adapted to be moved into a position for preventing the operation of said manual 85 means to move said bolt into its unlocking position when said roost is occupied.

7. In a device of the class described, the combination with a chicken coop having a door, of a bolt within said coop for retaining said door in a closed position, resilient means for automatically moving said bolt into its locking position, keepers for holding said bolt in its locking or unlocking position, resilient means associated with each of 90 said keepers for automatically moving them into their respective holding positions, means connected to each of said keepers, the actuation of which will move the keepers into positions out of holding engagement with said bolt, said coop having openings, means adapted to be inserted through said openings for actuating the means connected to said keepers for moving them out of their holding positions, means connected to said bolt, the actuation of which will move said 95

bolt into its unlocking position, said coop having a further opening, means adapted to be inserted through the last mentioned opening for actuating the means connected to said bolt for moving the latter into its 70 unlocking position, and means controlled by the chickens within the coop for preventing the insertion of the last mentioned means.

8. In a device of the class described, the combination with a coop having a door, of a bolt positioned within the coop, means for moving said bolt for holding said door in a closed position, automatically operated means for retaining said bolt in its holding position, said coop having a pair of openings, means adapted to be inserted through one of said openings for manually actuating the automatically operated means for releasing said bolt, means adapted to be inserted through the second opening for 85 moving said bolt for releasing said door, and means controlled by the chickens for preventing insertion of the last mentioned means.

9. In a device of the class described, the combination with a coop having a door, of a bolt positioned within the coop, resilient means for moving said bolt for holding said door in a closed position, said coop having an opening, a key adapted to be inserted 90 through said opening for moving said bolt for releasing said door, and means controlled by the chickens for preventing the insertion of said last mentioned means.

10. In a device of the class described, the combination with a coop having a door, of a bolt positioned within said coop, a spring for moving said bolt into its locking position, a spring actuated keeper for holding said bolt in its locking position, means for 105 moving said bolt into its unlocking position, a spring actuated keeper for holding said bolt in its unlocked position, a plurality of key holes formed in said coop, a plurality of keys adapted 110 to be inserted through said key holes for operating the spring actuated keepers and the means for moving said bolt into its unlocking position, and means controlled from within said coop for preventing the insertion of the key for operating the means employed for moving the bolt into its unlocking position.

11. In a device of the class described, the combination with a coop having a door, of a bolt positioned within the coop, a spring for moving said bolt for holding said door in a closed position, a spring actuated keeper for retaining said bolt in its holding position, said coop having a pair of openings, 120 a key adapted to be inserted through one of said openings for manually actuating the spring actuated keeper for releasing said bolt, a key adapted to be inserted through the second opening for moving said bolt 125 130

for releasing said door, and means controlled by the chickens for preventing the insertion of the last mentioned means.

12. In a device of the class described, the combination with a coop having a door, of a bolt for holding said door in its closed position, a pair of spring actuated keepers for retaining said bolt in its locking and unlocking positions, manually operated means for moving said bolt into its unlocking position, and means controlled by the chickens within the coop for preventing the operation of the last mentioned means.

13. In a device of the class described, the

combination with a coop having a door, of a bolt positioned within said coop adapted for retaining said door in its closed position, a tension spring for moving said bolt into its locking position, manually operable means for moving said bolt into its unlocking position, and a resiliently supported roost within said coop adapted to be moved into a position for preventing the operation of said manual means employed for moving said bolt into its unlocking position, when said roost is occupied.

In testimony whereof I affix my signature.

STANLEY STEMPKOSKI.
